STOP MOTIONS OF TEXTILE APPARATUS

Izchak Blum, Paris, France, assignor to Society
Comptoir d'Appareils Textiles, Société à Ré-
sponsabilité Limitée, Riedisheim, near Mul-
house (Haut-Rhin), France

Application April 24, 1933, Serial No. 667,721
In France May 26, 1932

1 Claim. (Cl. 139—268)

The invention relates to drop "wires" or blades in a textile apparatus, through which are threaded yarns, such as warps of a loom during weaving, or yarns being wound in a winding frame 5 or the like, and which wires or blades—hereinafter referred to as blades—co-operate with any form of apparatus for causing the loom or machine to stop when a yarn breaks, thus permitting the dropping of the blade to actuate the 10 stop motion, mechanical, electrical or otherwise.

At present such blades, whether of the closed or open type, are of flat and very thin metal and have formed therein an eye for the threading of the yarn. Figures 7, 8 and 9 of the annexed drawings show such a blade *b*, and are inserted by way of explanation, Figure 7 being a side view; Figure 8 an edge view; and Figure 9 a cross section. Thread eye *a* is cut in the metal to form an orifice in the plane thereof; *d* is the usual bar on which the blade drops on breakage 20 of the yarn *c*, which supports such blade.

With the form of eye shown disadvantages have been recognized. The yarn *c* in its passage through such an eye makes two distinct bends 25 with two changes of direction, with friction against the edges of the eye and the adjacent parts of the blade. This is clearly indicated in Figures 7 and 9. Further, when for example a group of warps is cut, the blades mounted on the 30 warps are huddled together—see the schematic view in plan of Figure 10, which figure is also inserted by way of explanation—and each warp, such as *c*² for example, rubs not only on the edge of the eye of its own blade *b*² but also 35 against the lateral edges of the adjacent blades *b*¹ and *b*³.

The total result of these frictional contacts of thread and blade is a scratching or even breakages of yarns, and moreover a large part 40 of the sizing of warps is removed by the scraping contact, with consequent inconveniences and difficulties in the later manipulation of the yarns.

Finally, there is the disadvantage that the blade due to the operation, already explained in 45 which a yarn enters and leaves the eye *a*, takes a position which is oblique to the yarn which supports it and also is oblique to the stop rod operated by the falling of the blade. This relative position of yarn, blade and stop rod prevents the blade from falling properly to perform 50 its function when the yarn breaks.

The object of the present invention is to provide means for the removal of the disadvantages 55 enumerated above, and in accordance with such invention the blade, instead of being flat at

the eye and thus compelling a yarn to twist as it goes through the blade eye, is itself distorted at the point where the eye is situated so that the yarn will pass in a straight line through the eye. By such construction the friction of the thread passing through the eye of the blade is lessened.

For a full understanding of the invention two constructions of a blade according to such invention will now be described by way of example, reference being had to the drawings annexed hereto wherein:

Figure 1 is an elevation—looking from the side of a machine in which it is mounted—of a blade of the closed type constructed according to the present invention:

Figure 2 is a horizontal section taken through the yarn eye of Figure 1;

Figures 3 and 4 are views corresponding to Figures 1 and 2 respectively, but showing a blade of the open type, with the present invention applied thereto:

Figure 5 is an edge view of part of a blade according to Figures 1 and 3; and

Figure 6 shows in horizontal across section a group of blades constructed according to this invention and mounted upon their yarns.

Figures 7 to 10 inclusive are given as before stated merely by way of explanation of existing blades, and form no part of this description of the present invention. They will not be further referred to;

Figure 11 is an elevation of a further embodiment of the invention in an open type blade;

Figure 12 is a fragmentary view on an enlarged scale of the eye of the blade shown in Figure 11;

Figure 13 is a side view of the detail of Figure 12; and

Figure 14 is a view similar to that of Figure 11 but showing a blade of the closed type.

From an examination of Figures 1 to 6 inclusive of the drawings it will be clear that the eye *a* of the blade *b* is surrounded by a zone of which a part *2* is pushed forward and the other part *3* pushed in the opposite direction. The parts *2* and *3* of the blade so deformed provide bowed projections extending from opposite faces of the blade, with the outer part of each projection forming a flat surface parallel to the plane of the blade. The projections are flared outwardly toward the edges of the blade so that the length of the flares along the blade edges is greater than the longitudinal dimension of the eye. Thus the eye *a*, constituting a passage for the yarn, presents when the edge of the blade *b* is viewed—Figure 5—an approxi-
